(57) CLAIM

The ornamental design for a spa chair pedestal, as shown and described.

DESCRIPTION

FIG. 1 is a perspective view of a spa chair pedestal in accordance with the invention;

FIG. 2 is a perspective view of the spa chair pedestal shown in FIG. 1 with the chair and basin removed;

FIG. 3 is a front view of the spa chair pedestal shown in FIGS. 1 and 2;

FIG. 4 is a rear view of the spa chair pedestal shown in FIGS. 1 and 2;

FIG. 5 is a top elevational view of the spa chair pedestal shown in FIGS. 1 and 2; and

FIG. 6 is a right side elevational view of the spa chair pedestal shown in FIGS. 1 and 2, the left side being a mirror image thereof.

The broken lines shown in FIGS. 1–6 illustrate portions of the spa chair pedestal that form no part of the claimed design. The additional broken lines shown in FIG. 1 show environmental subject matter that forms no part of the claimed design.
